UNITED STATES PATENT OFFICE.

ABRAM WAKEMAN, JR., OF NEW YORK, N. Y.

COFFEE-CLEANER.

SPECIFICATION forming part of Letters Patent No. 247,716, dated September 27, 1881.

Application filed January 20, 1881. (No model.)

To all whom it may concern:

Be it known that I, ABRAM WAKEMAN, Jr., of the city, county, and State of New York, have invented a new and useful Improvement 5 in Coffee-Cleaners, of which the following is a specification.

Figure 1, Sheet 1, is a sectional side elevation of the improvement. Fig. 2, Sheet 2, is an elevation of the inlet end of the same. Fig. 10 3, Sheet 2, is an elevation of the discharge end of the same. Fig. 4, Sheet 2, is a sectional end elevation of the cleaner taken through the line *x x*, Fig. 1. Fig. 5, Sheet 2, is a sectional end elevation of the cleaner taken through the line *y y*, Fig. 1.

Similar letters of reference indicate corresponding parts.

The object of this invention is to facilitate the removal of dust and other impurities from 20 coffee-berries.

In the accompanying drawings, A represents the supporting-frame, to which are attached bearings in which revolve the hollow journals B of the cylinder C. The cylinder C is set in a slightly-inclined position, and its lower end or head, E, is attached directly to its journal B. The upper end of the cylinder C is connected with its journal B by radial arms D. The middle part, F, of the upper head of the 25 cylinder C is separate, overlaps the outer or ring part, G, and is held stationary by being connected with the frame A by hinged bolts H, or other suitable means. In the stationary middle part, F, of the upper head is formed an opening to receive the lower end of the feed-spout I, the upper end of which is connected with the hopper J. The hopper J is attached to the frame A, and is provided at its discharge-opening with a valve, K, so that the feed can be regulated as desired. The upper part of the shell of the cylinder C is formed of wire-gauze L, or other suitable material, to sift out the loose dirt that may be upon the coffee-berries. The middle and lower parts, M, of the shell of the 30 cylinder C are formed of wood or other suitable material, and are provided with inwardly-projecting spikes N, as shown in Figs. 1 and 5. To the inner surface of the shell of the cylinder C are attached longitudinal bars or ribs 35 O, to serve as buckets to carry up the coffee-berries as the said cylinder is revolved.

P is an inner cylinder, the lower end of which revolves upon the inwardly-projecting end of the hollow journal B, or is provided with a hollow journal which passes through and revolves 55 in the said hollow journal B. To the upper end of the cylinder P is attached a hollow journal, Q, which passes through and revolves in the hollow journal B of the outer cylinder, C. The shell of the inner cylinder, P, is formed 60 of wood lined with metal, or of other suitable material, and is provided with outwardly-projecting spikes R. The shell of the inner cylinder, P, is provided with numerous small holes, as shown in Figs. 1 and 5, for the passage of 65 air, and has a partition, S, at a little distance from its lower end, dividing its interior into two unequal compartments, as shown in Fig. 1. To the projecting end of the upper hollow bearing, B, is attached a large pulley, T, to receive a driving-belt, and to the projecting end of the upper hollow journal, Q, of the inner cylinder, P, is attached a small pulley, U, to receive a driving-belt, so that the inner cylinder, P, will be driven at a much greater speed 70 than the outer cylinder, C. The two cylinders are driven in opposite directions.

V is a coiled pipe placed within the hollow cylinder P, and the ends of which are connected with or pass through the hollow journals of the cylinder P, so that steam can enter 75 through the upper journal and escape through the lower journal. The part of the steam-pipe V that passes through the small compartment at the lower end of the cylinder P is straight, 80 and is perforated with a number of fine holes to allow enough steam to escape to properly moisten the coffee-berries before they escape 85 from the cylinder C. In the lower end of the cylinder C, at or near its outer edge, are formed a number of openings, W, through which the coffee-berries escape. In the side of the cylinder C is formed a man-hole, X, which is closed 90 by a cap-plate, Y. The cylinder C is strengthened by hoops Z, as shown in Fig. 1.

In using the machine the coffee-berries are introduced into the upper end of the cylinder C, and the loose dirt escapes through the screen L. As the berries pass slowly down through the space between the cylinders C P they are carried up by the ribs O and are discharged 95 upon the spikes R of the inner cylinder, P, and

are projected from the inner cylinder, P, by the rapid revolution of the said cylinder P against the spikes of the outer cylinder, C, so that the berries will pass back and forth between the spiked shells of the two cylinders, being all the time rubbing against each other and the spikes, and will have all the dirt rubbed, scraped, and knocked off before the said berries reach the discharge end of the cylinder C. 5
As the berries pass toward the lower part of the machine they are dried by the heat from the steam-pipe V, to cause the dirt to rub off more easily, and as they approach the lower end of the machine they are moistened by the steam from the perforated part of the said steam-pipe V, so that they will contain about the same amount of moisture when they are discharged as when they entered the machine. 10
The inclination of the cylinders CP, and con-

sequently the rapidity of feed, is regulated by 20 raising and lowering the bearings at the lower end of the machine.

Having thus fully described my invention, I claim as new and desire to secure by Letters Patent—

In a coffee-cleaner, the combination of two oppositely-revolving cylinders, C P, the outer one having spikes and longitudinal ribs on the inside and the inner cylinder provided with spikes on the outside, whereby the berries may be introduced between the cylinders, carried up by the ribs, dropped on the spikes of the inner cylinder, and thence thrown against the spikes of the outer cylinder, as described. 25
